TANDY A. BRYSON, OF TROY, NEW YORK, ASSIGNOR TO TOLHURST MACHINE WORKS,
A CORPORATION OF NEW YORK.

DRIVING MECHANISM AND METHOD.

Application filed February 12, 1921. Serial No. 444,444.

The invention relates to a method of operating an installation comprising an induction motor, a load to be driven at widely varying speeds, and an intervening power-transmitting and energy dissipating device, and also to mechanical driving means interposed between a motor and a machine driven thereby, and more particularly to a friction clutch and cooperating connections between 5 a driving motor and the machine driven thereby, designed to provide for widely different low and high speeds of the load, and for the motor getting up speed before taking the load, and in certain of its features 10 the invention is specially applicable to centrifugal extractors.

Objects and advantages of the invention will be set forth in part hereinafter and in part will be obvious herefrom, or may be 20 learned by practice with the invention, the same being realized and attained by means of instrumentalities and combinations pointed out in the appended claims.

The invention consists in the novel parts, 25 constructions, arrangements, combinations and improvements, herein shown and described.

The accompanying drawings, referred to herein and constituting a part hereof, illustrate one embodiment of the invention, and together with the description, serve to explain the principles of the invention.

Of the drawings:

Fig. 1 is an end elevation of a clutch embodying the invention;

Fig. 2 is a vertical, longitudinal section on line 2—2 of Fig. 1;

Fig. 3 is a detached side elevation of the centrifugally operated clutch member;

Fig. 4 shows the device of Fig. 3 looking thereat from the right;

Fig. 5 is a detached side elevation of the clutch member operated by the member shown in Figs. 3 and 4;

Fig. 6 shows the device of Fig. 5, looking thereat from the right;

(The devices shown detached in Figs. 3 to 6 are shown assembled in Figs. 1 and 2);

Fig. 7 shows the drive of the foregoing figures applied between an electric motor and a centrifugal machine; and

Fig. 8 is a diagram showing the operation of the motor and driving connections in a typical or illustrative case.

In providing a drive for centrifugal extractors it is desirable for rapid acceleration to have available a high and long sustained torque during the starting period. Further, in commercial work, it is often necessary to provide two widely different speeds of the 55 centrifugal machine, as for example, a high operating speed and a slow speed for unloading, which may be, for instance, only ten per cent of the high speed. When using an electric induction motor for driving, as is customary and desirable in such drives, this presents a problem which is met by this invention while avoiding the necessity for a specially designed or over-sized motor or expensive and complex electrical control 60 equipment, such as have been heretofore required for this purpose.

By my invention and with the employment of the standard low-resistance induction motor it is possible to secure both the 75 high operating speed and the before-mentioned low speed and at the same time provide for a quick acceleration when starting until the high speed is attained with a concurrent certain and safe control of the current inrush.

I may further in obtaining the reduced torque apply a reduced voltage to the primary winding of the induction motor, allowing a clutch device connecting the motor and 85 centrifugal to slip an amount equal to the difference in rotative speed of the motor and driven machine.

When it is desired to change from low to high speed, full voltage is applied to the 90 motor. Whether this will cause an excessive current inrush depends upon one or both of two conditions. It will not do so, first if the motor is so constructed that the current inrush is resisted, as for example in the high 95 resistance rotor type, which is generally used; second, if the motor when driving its load at low speed has been allowed to operate at a sufficiently high relative speed, i. e. if high rate of slip has been permitted in the 100 clutch on low speed.

If the latter condition obtains, a standard low-resistance rotor squirrel-cage motor may be used with several advantages over such a motor with a high resistance rotor. 105 The present invention comprises the use of such a low resistance motor with a novel clutch mechanism which will withhold ac-

tion until proper rotor speed is attained in the motor and will then cooperate properly and efficiently with changes in the torque and speed of the motor and in the speed of the load.

With further reference to the particular and exemplary application of the invention to driving centrifugal extractors, my invention will provide the two widely different speeds for the loaded centrifugal, and at no time during either of said speed periods, nor in changing from stop to low speed, or from low speed to high, does the current inrush exceed that allowed by the electric codes for induction motors, and accomplishes this with the standard low resistance squirrel cage motor.

If a reduced torque is obtained from a high-resistance motor by means of reduced voltage, the usual centrifugal clutch will absorb all of this torque at comparatively low speed, and cause the motor to develop a high percentage of slip with consequent heating in the motor. But with the low resistance motor and the delayed action clutch included in my invention, the reduced torque is not absorbed until the motor has attained a comparatively high speed, thus permitting most of the slip to occur in the clutch where means may be and are provided for its dissipation without injury to the motor or other parts.

Continuing the comparison, the high resistance motor has a characteristic relation between its speed and delivered torque such that it produces its maximum turning effort at a relatively low speed and as speed increases, the delivered torque rapidly decreases. To obtain advantage of a high accelerating torque when high speed connection is made, the ordinary centrifugal clutch used must be designed to absorb all of the available motor torque at an early stage in the accelerating period of the motor. This is also objectionable in that it causes high magnetic slip and heating, and that the remainder of the acceleration of motor and machine is accomplished under rapidly decreasing torque. On the other hand, the low resistance motor, the use of which is permitted by my invention, develops its maximum torque at about eighty per cent synchronous speed. By my invention, the clutch may be made to take hold, or connect up at, or approximately at, this speed or point of maximum torque.

When high or full speed is desired at the centrifugal, full voltage is supplied to the motor and, since, as has been stated, the motor is already at high speed, the available torque immediately rises to near the maximum value for the motor. The clutch, after a slight amount of acceleration, is able to absorb the increased torque so that the motor cannot increase in speed until the centrifugal machine, which is now receiving the

excess torque, is accelerated up to this same speed. The result is that practically throughout the accelerating period, the centrifugal receives torque from the peak, or near the peak of the motor torque curve, and therefore the acceleration is rapid, with consequent reduction in motor capacity required for a given duty cycle and load. Since both of the centrifugal speeds are obtained from high motor speeds, it is obvious that the change from reduced to full voltage will not cause a severe current disturbance.

The illustrated embodiment in its main features comprises a driving member rotating with the motor shaft, and an adjacent driven member connected to a belt pulley or other connection to the driven machine, and a clutch device between the driving and driven members, the clutching action being determined or controlled by a centrifugally operated device and a spring cooperating or working against each other, the parts being proportioned and weighted to effect the clutching action at a predetermined speed of the motor shaft. The spring tension is variable or adjustable to effect changes in the predetermined motor or shaft speed at which the clutch engagement occurs.

More in detail, a flat disc is fixed on the motor shaft to rotate therewith, and adjacent thereto is a friction drum to which is fixed a belt pulley, and encircling the drum is a clutch band.

To one end of the clutch band is pivoted a lever mounted upon and concentrically with the disc fixed on the motor shaft. A second lever is pivotally connected to the other end of the clutch band, and is likewise mounted upon and concentrically with the driving disc.

Pivoted on one of the levers, or on a ring fixed to or integral therewith are a plurality of arms to the outer ends of which are attached weights. The arms so mounted on said lever have geared connection with a geared circle or plate fixed to and concentric with the other lever, whereby the two levers move concurrently but in opposite directions, by which movement the clutch band is loosened to release the drum or tightened to clutch the drum.

Projecting from each of the lever structures is an arm, and between the two arms is a spring tending to press the arms together. When the disc is rotating the weights tend to swing outwardly under centrifugal force against the pressure of the spring. When the centrifugal force has reached a certain intensity of power, the spring is compressed to a degree where the clutch band clutches the drum to effect the driving action. The parts are so proportioned and weighted, and the spring pres-

sure is so regulated that the clutching action takes place at the desired or predetermined speed of the motor.

Referring now in detail to the specific structure, illustrated by way of example in the accompanying drawings, the invention is shown applied to the drive of a centrifugal machine, although it will be understood that it has application in the drive of other machines.

As exemplified, a centrifugal machine 1 is shown having a driving pulley 2, over which runs a driving belt 3. The belt 3 runs over a guiding pulley 4 and is driven from the device or mechanism 5, to which the present invention in certain of its structural features more particularly relates, the entire mechanism being driven from the motor 6.

Fixed on the shaft 10 of the motor 6 is a sleeve 11, keyed to the shaft by a key 12. Sleeve 11 comprises an external bearing hub 13, from which hub projects radially an arm, or a plurality of arms 14, from which is supported a ring 15 concentric with the shaft 10. Projecting from the ring 15 is a radially disposed arm 16, to which is pivotally connected one end of a clutching band 17, the band being connected to the arm 16 by means of a pin 19 fitting in a hub 20 formed in the exterior end of the arm. The clutch band 17 encircles the exterior of a pulley drum as will be later described.

Cooperating with the mechanism just described are devices adapted to cause the band 17 to engage the pulley drum at a predetermined speed, such devices operating by centrifugal action opposed by a spring, the tension of which is settable or regulable as desired. In the embodied form thereof, mounted on the exterior of the sleeve 11 is a sleeve 24, from which sleeve projects an annular plate 25, fixed to or integral with the sleeve. Projecting radially from the annular plate or disc 25 is an arm 26 which has formed in the end thereof a hub 27, in which is carried a pin 28 to which pin the other end of the clutch band 17 is attached.

The arms 16 and 26 extend radially and are relatively close to each other, the clutch band 17 being connected to each of these arms and encircling the pulley drum. As the arms 16 and 26 recede circumferentially from each other, the clutch band 17 releases the pulley drum, and as arms 16 and 26 are drawn toward each other, through connections and by devices later to be described, clutch band 17 tightens about the pulley drum and drives the pulley and its load.

In the embodied form of centrifugally operated and spring controlled mechanism, there are formed in the periphery of the plate or disc 25 groups or series of gear teeth 31, three such groups being shown.

Formed in the ring 15 are three correspond-

ing hubs 32, in which are mounted pins or shafts 33. Upon the shafts 33, respectively, are mounted discs or wheels 34, provided with gear teeth 35, which mesh with the gear teeth 31 upon the disc 25. Projecting from each of the discs or wheels 34 is an arm 36, carrying at its outer end a weight 37.

Fixed or integral with the disc or plate 25 is an arm 40 and pivotally mounted on a pin 41 in the exterior end thereof is a rod 42. Fixed to or integral with the ring 15 is an arm 43 and projecting from the outer end thereof is a lug or pin 44, internally apertured, the rod 42 projecting therethrough. Encircling the rod 42 is a coiled spring 45, in tension between the lug 44 and a nut 46, screw-threaded on the external end of the rod 42. By screwing and unscrewing the nut 46 the tension of the spring 45 may be changed, and thus the force yieldingly drawing the arms 40 and 43 together may be varied.

The yielding and regulable spring action so exerted tends to move apart the arms 16 and 26, and to keep them yieldingly or resiliently held apart, and to keep the clutch band 17 loose about the pulley drum. As the shaft 10 rotates, centrifugal force will move the weights 37 outwardly, and through the action of the gear teeth 35 and 31 will draw the arms 16 and 26 together in opposition to the pressure of the spring 45. The action or pressure of the spring remains fixed or constant, at the desired predetermined setting, while the force or power of the weights 37 increase with the speed of rotation of the shaft 10, thus the clutching or engaging action of the clutch band 17 will take place at any desired speed of rotation of the shaft 10, this being the speed at which the weights 37 through centrifugal action overcome the spring 45.

So far as concerns many features of the invention, the pulley mechanism may be of any desired form. As herein shown a friction sleeve 50 is loose on shaft 10 and sleeved thereon is a hub 51 of the pulley 52. At its inner end pulley 52 is fixed or integral with a disc member 53, the disc 53 at its outer or peripheral end terminating in an annular or crown flange 54 extending perpendicularly from the flat face of the disc 53 and constituting the clutch drum.

With reference to those features of the invention which relate to motor and current control, in addition to the feature of avoiding excessive current inrush already discussed, my invention renders possible the use of an induction motor to drive a centrifugal under all the sharply varying conditions of load, including acceleration of load to high speed, maintenance of the load at high speed during the drying operation, and running the load at low speed during unloading, as for instance, when sugar is

unloaded by a plow or unloading device. The speed of the rotating field is practically constant at all voltages, and the relative speed of the rotor is in itself unimportant, 5 in so far as the speed of the load is concerned, but some change of rotor speed is necessary to alter the torque of the clutch to improve the efficiency. The substantially fixed speeds are those of the rotating 10 magnetic field and of the basket, and the difference in these two speeds under various conditions can be allowed for by the slipping of the clutch. By reducing the torque during the period of slow rotation 15 of the load, the amount of energy which must be dissipated by the clutch, to permit the relatively high speed of the rotor, is reduced to a practical minimum. A large amount of slip of the rotor is objectionable 20 during that part of the operation cycle when it is desired to have the load speed less than the motor speed, because of the lower power factor, and of the heating of the motor.

Referring in detail to an exemplary operating cycle shown graphically in Fig. 8, the operation as shown in said figure is as follows:—

Low voltage is applied to the motor, which accelerates until it reaches 70 per 30 cent of synchronous speed, when the clutch comes into action and supplies an accelerating torque to the load, the rotor and load running at different speeds until the "clutch torque" curve intersects the "torque at reduced voltage" curve, after which the rotor and load accelerate together until high voltage is applied.

The application of high voltage increases the torque of the motor, which again causes 40 it to accelerate faster than the load until the speed corresponding to the intersection of the "clutch torque" and "full voltage torque" is reached at 87 per cent of synchronous speed. After this point is reached, 45 rotor and load accelerate together until a speed is reached at which the motor develops just sufficient torque to run the load at constant speed.

Under this condition the motor is running inefficiently because it is carrying only 50 one-quarter of full load. To increase the efficiency of the motor the voltage is reduced, which in turn reduces the amount of magnetizing current taken by the motor, 55 and increases its efficiency and its power factor. This lowering of the voltage also produces a small reduction in speed.

When it is necessary to still further reduce the speed of the load for unloading 60 purposes, an additional drag on the load causes the rotor to slow down until a speed corresponding to the intersection of the "clutch torque" and "torque at reduced voltage" is reached, when the clutch begins to slip thus limiting the output of the motor.

As the load speed is still further reduced, for unloading, the power represented by the product of the difference in speed between rotor and load times the torque of the clutch is dissipated as heat in the clutch by mechanical friction.

Had low voltage not been used, the additional drag on the load for unloading would have caused the rotor to slow down along the "full voltage torque" curve until the 75 point of intersection of this "full voltage torque" curve with the "clutch torque" curve is reached, when the clutch begins to slip, allowing the motor to run at this constant speed, while the load speed is reduced to 80 the value required for unloading. The power represented by the difference in speed between the rotor and load times the clutch torque is dissipated as heat in the clutch by 85 mechanical friction.

By reference to Fig. 8 it is seen that by reducing the voltage for the unloading operation, the speed of the rotor at which the clutch slips is reduced from 87 per cent to 77 per cent of synchronous speed, and that this change in speed reduces the slipping torque from 200 foot pounds to 70 foot 90 pounds. This means that the power that must be dissipated in the clutch when using low voltage is only about one-third the 95 power dissipated by the clutch at full voltage. In other words, the efficiency is higher, and the heating of motor and clutch is lower.

Through my invention, I realize and attain several very important novel advantages a.i.1 results, namely, I obtain the requisite widely varying speeds of load, as the high speed in drying the charge in the centrifugal and the very low speed in then unloading the dried charge, as by a plow unloader. I also retain the advantages of the ruggedness and simplicity of the squirrel cage motor (although not limited thereto), the disadvantage of which heretofore has been its inherent constant speed characteristic; and I also maintain high operating efficiency by retaining a relatively high, but reduced, speed of the motor and at the same time reducing the amount of energy to be dissipated at the clutch to an approximate minimum. I thus maintain the motor of this type at a very high ratio of efficiency and further transmit an unusually high proportion of the resultant mechanical energy into 110 the useful work on the load, while rotating the centrifugal basket at the very low speed necessary in this kind of unloading.

It will be understood that this typical illustration is exemplary of the operation of the invention and is no wise restrictive thereof. The invention may be applied to any power developing device whose speed torque characteristics are such as may make its use 125 advantageous.

The invention in its broader aspects is not limited to the specific mechanisms shown and described but departures may be made therefrom within the scope of the accompanying claims without departing from the principles of the invention and without sacrificing its chief advantages.

What I claim is:—

1. The combination of an induction motor, an alternating current supply of constant frequency arranged to supply the motor at various voltages, and a speed responsive clutch for connecting the motor to its load, the torque transmitting power of the clutch being less than the torque producing power of the motor until the motor has at least attained a speed corresponding to its maximum torque for a given voltage.

2. The combination of an induction motor, an alternating current supply of constant frequency for supplying the motor with a high or a low voltage, and a speed responsive clutch for connecting the motor to its load, the torque transmitting power of the clutch being continually less than the torque producing power of the motor on either high or low voltage until the motor has at least attained a speed corresponding to its maximum torque for that voltage.

3. The combination of an induction motor, an alternating current supply of constant frequency, means for supplying a low voltage to the motor from said current supply for handling a light load and for supplying a high voltage to the motor for handling a full load, and a speed responsive clutch connecting the motor to its load, for fixing the value of the reduced torque and full torque for the light and full loads, respectively, the motor speed for the reduced torque and full torque in each case being substantially that speed corresponding to its maximum torque for that voltage.

4. The combination of an induction motor, a multi-voltage alternating current supply of constant frequency, arranged to supply the motor with current at various voltages, and a speed responsive clutch for connecting the motor to its load, the torque transmitting power speed characteristic of the clutch being such that it crosses the torque-speed characteristic of the motor above the maximum torque point for a plurality of operating voltages whereby the load may be driven at lower speed than the motor.

5. The method of operating an installation comprising an induction motor, a variable load, and a mechanical driving connection therebetween, of which the torque transmitting power is less under any conditions of operation than the maximum torque of the motor, which comprises impressing a high voltage to accelerate the load, reducing this voltage for normal running, in-

creasing the torque demand of the load above the torque transmitting power of the driving connection, whereby the load is driven at lower speed than the motor, and the motor operates above the speed for maximum torque.

6. The method of operating an installation comprising an induction motor, a variable load, and a mechanical driving connection therebetween, of which the torque transmitting power is less under any conditions of operation than the maximum torque of the motor, which comprises impressing an alternating voltage of definite frequency on the motor, temporarily increasing the magnitude only of said voltage to accelerate the load, maintaining the original magnitude of said voltage for normal running, increasing the torque demand of the load above the torque transmitting power of the driving connection, whereby the load is driven at lower speed than the motor and the motor operates above the speed for maximum torque.

7. The method of operating an installation comprising an induction motor, a variable load, and a mechanical driving connection therebetween, of which the torque transmitting power is less under any conditions of operation than the maximum torque of the motor, which comprises impressing a high voltage to accelerate the load, reducing this voltage for normal running, increasing the torque demand of the load above the torque transmitting power of the driving connection, whereby the load is driven at lower speed than the motor, and the motor operates above the speed for maximum torque, the surplus energy transmitted from the motor being dissipated in the driving connection.

8. The method of operating an installation comprising an induction motor, a variable load, and a mechanical driving connection therebetween, which comprises successively impressing different voltages to effect variations in the motor torque to meet varying conditions of acceleration, speed and amount of load, and limiting the current inflow under said varying conditions by causing the motor rotor to run at relatively high speed under all load conditions to avoid heating and low power factor, and controlling the amount of surplus energy transmitted from the motor to be dissipated in the driving connection.

9. The method of operating an installation comprising an induction motor, a centrifugal and a mechanical driving connection therebetween of which the torque transmitting power is less, under the conditions of operation, than the maximum torque of the motor, which comprises impressing a high voltage of definite frequency on the motor to increase the speed of the centrif-

ugal, reducing the voltage during the running of the centrifugal at normal speed, increasing the load torque for unloading, thereby greatly reducing the speed of the centrifugal while the motor continues to run at a speed above the speed of maximum torque and the surplus energy transmitted from the motor is dissipated in the driving connection.

10. The method of operating an installation comprising an induction motor, a variable load, and a mechanical driving connection therebetween, of which the torque transmitting power is less under any condi-

tions of operation than the maximum torque 15 of the motor, which comprises successively impressing different voltages to vary by a relatively small amount the speed of the motor, thereby varying by a corresponding relatively large amount the torque produced 20 by the clutch to determine the energy drawn from the motor, the amount of surplus energy developed and to dissipate same at the clutch.

In testimony whereof, I have signed my 25 name to this specification.

TANDY A. BRYSON.
